UNITED STATES PATENT OFFICE.

GILBERT C. BEMIS, OF WORCESTER, MASSACHUSETTS, ASSIGNOR TO WORCESTER BRUSH AND SCRAPER COMPANY, OF WORCESTER, MASSACHUSETTS, A CORPORATION OF MASSACHUSETTS.

BRUSH FOR CLEANING GUNS AND THE LIKE.

1,258,737.

Specification of Letters Patent. Patented Mar. 12, 1918.

Application filed April 6, 1917. Serial No. 160,288.

To all whom it may concern:

Be it known that I, GILBERT C. BEMIS, a citizen of the United States, residing at Worcester, in the county of Worcester and State of Massachusetts, have invented a new and useful Brush for Cleaning Guns and the Like, of which the following is a specification.

This invention relates to a brush, which can be made of any shape according to the use to which it is to be put, but is made preferably of cylindrical form so that it can be used for cleaning out cannon and the like.

The principal objects of the invention are to provide a simple, convenient and light construction which can be made up of a number of separate replaceable elements of such a character that the brush will not be excessively heavy and the brush fillers can be replaced readily and at small expense when worn; to provide a construction in which the bristles will have a maximum cleaning effect so that the device will remove particles of copper and other metals from the interior of the bore of a gun; to provide an improved way of holding and clamping the brush fillers; to provide a simple yet effective means for more positively holding the fillers in position by applying pressure to the circumference of the brush; to provide means whereby the depth to which the fillers are placed in the brush structure will be gaged by a member separate from the separator disks which provide the sockets therefor so that the cost of these disks can be reduced by eliminating the necessity of some of the precision of the operations necessary to make them; to provide means for supporting a brush, particularly one with soft bristles, in spite of the weight of the parts so that when it is used in cleaning out a cannon both its upper and lower bristles will come into action against the corresponding interior surfaces of the gun; to provide for extreme lightness by making the parts of aluminum, and especially to provide a construction which will be particularly efficient and durable for per-

forming the necessary operations in cleaning heavy guns.

Further objects and advantages of the invention will appear hereinafter.

Reference is to be had to the accompanying drawings, in which—

Figure 1 is a side view of a brush of small size constructed in accordance with this invention with parts in central longitudinal section;

Fig. 2 is a sectional view of the same on the line 2—2 of Fig. 1;

Fig. 3 is a face view of one of the separator disks for holding the brush elements in position;

Fig. 4 is an edge view of the same; 65

Fig. 5 is a view similar to Fig. 1 showing a modified construction;

Fig. 6 is a face view of one of the disks used thereon;

Fig. 7 is an edge view of the same; 70

Fig. 8 is a view similar to Fig. 1 of another modification in which the separator disks are made of wood, and

Fig. 9 is a sectional view on the line 9—9 in Fig. 8. 75

Referring first to the first sheet of drawings, it will be seen that the gun cleaning brush as shown therein comprises a hollow metallic core 10 which I prefer to make of aluminum. This is provided with an integral axial projection 11 also hollow, which has provisions in the way of perforations or the like 12 for attachment to the handle by which it is manipulated.

The core 10 is provided with a flange 13 at one end and with a washer 14 at the other end. These are both arranged to have full thickness at their edges, but are recessed elsewhere as at 15 so that the full width edges at their circumference will press against the outer edges of a series of separators in the form of aluminum disks 16 when fastened in position by means of a nut 17 on the end of the core 10. This nut is also constructed in the same way preferably, so as to get the pressure out at the circumference. 80 90 95

The disks 16 are provided with semi-cir-

cular recesses 18 on both sides, but these are not in registration with each other on the two sides, being offset slightly as indicated for a purpose that will appear. All of these disks or separators except the two end ones are provided with recesses on both sides, and those in the adjacent disks register with each other so as to form cylindrical sockets for the butts 21 of a series of brush fillers 20. The recesses are not fully semi-circular so that when the separators are clamped together the pressure will come on the butts 21 and hold them firmly.

These metallic butts are shown as provided with circumferential grooves 22, one in each one, for two purposes. One purpose is to enable them to pinch the bristles 23 which in this form are indicated as of wire, and the other purpose is to arrange for holding them firmly in position and prevent their displacement radially. It is to be noted that the gripping of the disks at their circumferences in the manner that has been described serves to accomplish this result, but an additional means is also shown in the form of a series of circular metallic plates 24. These plates are placed between each two adjacent disks but are not intended to fill the entire space between them because it is desired to get an efficient gripping action on the bases of the brush elements, and consequently the disks are not intended to touch each other or the plates 24 when tightened up against the brush butts. But these plates are thick enough so that they are held substantially in stationary position, and they are provided with notches 25 into which the brush ends set, and these notches are provided with opposite projections or lugs 26 integral with them which fit into the circumferential recesses 22 and positively prevent displacement of the brushes radially in addition to the action above described.

Another feature is shown in these figures which is ordinarily not used when the brush elements are provided with metallic bristles, but is of particular use when they are made of soft bristles. In that case on account of the weight of the brush there would be a tendency for it to drop down when used for cleaning guns so that the upper brushes would not act on the inner surface of the bore. For the purpose of preventing this and supporting the brush in a substantially central position a member 28 is provided between the two circumferential rows of bristles for supporting the brush at the bottom in case this difficulty occurs. In this form of the invention this is shown as an integral circular projection on one of the disks 16 and as extending all the way around so that they will not dig in to the surface of the cannon.

In the form shown in Figs. 5, 6 and 7 many of the same features are illustrated, and this form also is made of aluminum. Here the central core 30 is of larger diameter than in the other case, but is arranged in a similar manner except that it is open at the end. In this case a ring 34 is arranged at the outer end and held toward the flange 33 by bolts 35 which extend through cored recesses 37 in the cast aluminum disks 36. It will not be necessary to describe these disks as they are shown as made substantially like those shown in Fig. 1 with the omission of some parts, and they are cored out instead of solid. They support the brush elements 20 and in this case the plates 24 are omitted, but it will be seen that the bolts 35 are located at the circumstances substantially so as to grip the outer edges of the brush butts and prevent their displacement. This is an important feature either in this form or in the form shown in Fig. 1 because as made heretofore the pressure has been uniform from end to end and has been distributed along the length of these metallic butts so that it was too much divided up and they sometimes got loosened and came out, thus necessitating loss of time and sometimes injuring the device being cleaned. The core 30 limits the position of the brush fillers.

In the form shown in Figs. 8 and 9 a large size cannon cleaner is also shown, but in this case the metal core 40 is provided with a larger flange 43 which is recessed out at the center at 45 and the nut 44 is arranged in the same way so that pressure is secured at the extreme circumference. In this case, however, the core 40 does not serve any function except to center a series of wooden separator disks 46 and receive the fastening nut 47. In this case I have shown the sheet metal plates 24 having the recesses 25 for the butts of the brushes and the projections 26 entering the circumferential grooves 22 as in Fig. 1. This is an important feature in the case of a large wooden brush especially because without it the disks would have to be bored to provide the sockets for the brush heads, and this boring would have to be done with a great deal of precision in order that the ends of the bores might serve to limit the position of the brushes uniformly and cause them to project to uniform distances from the circumferences of the disks. This I avoid by the use of these plates which are stamped out very economically and permit the boring of these sockets to non-uniform depths without injuring the brush or making it non-circular.

Although I have illustrated and described several forms of the invention I am aware of the fact that other modifications can be

made therein by any person skilled in the art without departing from the scope of the invention as expressed in the claims. Therefore I do not wish to be limited to all the details of construction herein shown and described, but what I do claim is:—

1. In a brush, the combination of a plurality of separators each having a series of semi-cylindrical recesses in which the heads 10 of brush fillers can be placed at different distances from the center, and means separate from said separators for limiting the position of said fillers.

2. In a brush, the combination of a series 15 of separators each having substantially semi-cylindrical recesses in its face, whereby the recesses of two adjacent separators will form a socket in which the butt of a brush filler can be placed at different distances 20 from the center, and means independent of said separators but connected therewith for engaging the butt ends of the fillers and limiting their positions.

3. In a gun cleaner, the combination of 25 a series of disks each having semi-cylindrical recesses in its face whereby the recesses of two disks will form a socket for the head of a brush filler, and means clamped between said disks for engaging 30 the butt ends of the fillers and limiting their positions.

4. In a gun cleaner, the combination of a plurality of aluminum disks each having a series of semi-cylindrical recesses for the 35 heads of brush fillers, and a series of metal plates located between said disks for limiting the position of said fillers.

5. In a brush, the combination of a core, a plurality of separators located on said 40 core, and having registering recesses, brush fillers mounted in said recesses, and means for holding said separators on the core and applying more pressure to their exterior edges than to any other region so as to grip 45 the butts of said fillers at their outer ends.

6. In a brush for cleaning guns, the combination of a core, a plurality of separator disks located on said core, said separator disks having registering recesses, brush 50 fillers mounted in said recesses, and means for holding said separator disks on the core and applying pressure to their exterior edges so as to grip the butts of said fillers at their outer ends, said means comprising 55 a washer at the end of the core, said washer being of full thickness at its edge and recessed inside the edge, said edge bearing one the edge of the end separator disks, and means for fastening the washer in position.

7. In a brush the combination of a core, a plurality of disks located on said core, said disks having registering recesses, brush fillers mounted in said recesses, a washer at 60 the end of the core, said washer being of

full thickness at its edge and recessed inside 65 the edge, said edge bearing on the edge of the end disk, and means for fastening the washer in position for holding said disks on the core and applying pressure to their exterior edges so as to grip the butts of said 70 fillers at their outer ends.

8. In a brush, the combination of a core, a plurality of separators located on said core, having registering recesses, brush 75 fillers mounted in said recesses, and means for holding said separators on the core and applying pressure to their exterior edges so as to grip said fillers at their outer ends, said means comprising a series of bolts passing 80 from one end of the brush to the other and located near their circumferences to clamp the separators together.

9. In a brush, the combination of a core, a plurality of aluminum disks located on said core, said disks having registering recesses, brush fillers mounted in said recesses, and means for holding said disks on the core and applying pressure to the exterior edges of the disks so as to grip said fillers 90 at their outer ends, said means comprising a series of bolts passing from one end of the brush to the other and located near their circumferences to clamp the edges of the disks together, said disks having cored 95 passages through them for receiving said bolts.

10. In a gun cleaner, the combination of a series of disks each having semi-cylindrical recesses in its face whereby the recesses of two disks will form a socket for the head of a brush filler, means for engaging 100 the butt ends of the fillers and limiting their positions, and a support located between the fillers and extending radially to a point short of the ends of the bristles thereof for supporting a brush and keeping the fillers on both sides in contact with the interior of a cannon or the like.

11. In a gun cleaner, the combination of a plurality of separators each having a series of semi-cylindrical recesses for the butts of brush fillers, and means extending beyond the butts of said fillers but not out to the ends of the bristles for supporting 115 the separator substantially centrally in a gun or the like.

12. In a brush, the combination of a plurality of separators each having a series of semi-cylindrical recesses for the butts of brush fillers, means for limiting the position of said fillers, said means comprising a plurality of thin plates of circular form concentric with said separators and located between them, each one having a notch for receiving the head of a brush filler.

13. In a brush, the combination of a plurality of disks each having a series of recesses for the butts of brush fillers, thin

plates of circular form concentric with said disks and located between them, each one having a notch for receiving the butt of a brush filler, each of said notches having a pair of tongues projecting inwardly from its sides, said brush filler butts being pro-

vided with circumferential grooves into which said tongues project to prevent the displacement of the fillers radially.

In testimony whereof I have hereunto affixed my signature.

GILBERT C. BEMIS.
